DRINKING MOUTHPIECE FOR A CAN

Piero Simeoni, 4243 SW. Hill St., Seattle, Wash.

Filed Jan. 14, 1964, Ser. No. 78,192

Term of patent 3½ years

(Cl. D58—26)

FIG. 4 is a side elevational view thereof.

I claim:

The ornamental design for a drinking mouthpiece for a can, substantially as shown.
